(57) **CLAIM**

The ornamental design of a circular food container, as shown and described.

DESCRIPTION

FIG. 1 is a perspective view of the circular food container according to my design, as seen from above.

FIG. 2 is a perspective view of the circular food container of FIG. 1.

FIG. 3 is a perspective view of the circular food container of FIG. 1, as seen from below.

FIG. 4 is a perspective view of the circular food container of FIG. 1, as seen from above, with the lid separated.

FIG. 5 is a perspective view of the circular food container of FIG. 1, as seen from side, with the lid separated.

FIG. 6 is a perspective view of the circular food container of FIG. 1, as seen from below, with the lid separated.

FIG. 7 is a side view of the circular food container of FIG. 1.

FIG. 8 is a side view of the circular food container of FIG. 1, with the lid separated.

FIG. 9 is a top plan view of the circular food container of FIG. 1.

FIG. 10 is a bottom plan view of the circular food container of FIG. 1; and,

FIG. 11 is a across sectional view through line 11—11 of FIG. 1.
